UNITED STATES PATENT OFFICE.

ROBERT JOHN LYLE, OF KINMOUNT, ONTARIO, CANADA.

TROLLEY SHOE.

Application filed May 23, 1925. Serial No. 32,479.

To all whom it may concern:

Be it known that I, ROBERT JOHN LYLE, a subject of the King of Great Britain, and a resident of the village of Kinmount, in the county of Victoria, in the Province of Ontario, Canada, have invented certain new and useful Improvements in Trolley Shoes, of which the following is the specification.

My invention relates to improvements in trolley shoes, and the object of the invention is to devise a shoe which will have a plurality of wearing surfaces which may be used successively as a sliding contact, thereby providing a shoe which will have a maximum life, which in each contact position will be self adjusting to the forward and reverse movement and through which the current path of travel to the harp is equal in all positions, and it consists essentially of the arrangement and construction of parts as hereinafter more particularly explained.

Fig. 1 is a side elevation of my trolley shoe mounted upon a harp and shown in the position of forward travel as indicated by arrow.

Fig. 2 is a similar view to Figure 1 showing the shoe in position of rearward travel.

Fig. 3 is a sectional view through my shoe showing it mounted in the arms of the trolley harp.

In the drawings like characters of reference indicate corresponding parts in each figure.

1 indicates my shoe which is annular and provided with a surrounding groove 2 equal in depth at all points.

3 is a hub connected by spokes 4 to the annular shoe 1. The hub 3 is provided with a central orifice 5.

6 is a trolley harp provided with arms 7 and 8, each provided with an orifice 9.

10 is an axle pin extending through the orifices 9 of the arms and 5 of the shoe and held in place by cotter pins 11.

12 is a spring contact secured to each arm of the harp 6 and bearing against the end of the hub 3 around the axle pin 10 as clearly indicated in Figure 3.

50 By this means current conduction between the shoe and harp is provided for.

13 are projections extending from the trolley shoe and arranged circumferentially

therearound at equal spaced distances apart, preferably at a point of junction between each spoke 4 and the annular shoe 1.

14 is a rib extending inward from each arm 7 of the trolley harp in the path of movement of the projections 13.

When the shoe 1 is mounted upon the harp in operative position, the ribs 14 project inward between any one pair of projections 13 at each side of the shoe.

When the shoe is travelling in the forward direction as indicated by arrow in Figure 1, one of the projections 13 indicated by the numeral 13^x is carried against the rib 14 so as to engage the lower side thereof as clearly indicated in Figure 1, thereby holding the shoe from rotary movement during its forward travel so that the periphery of the shoe formed by the base of the groove 2 has sliding contact with the trolley wire indicated at 15. When the travel of the shoe 1 upon the trolley wire 15 is reversed, one of the projections 13 indicated by the numeral 13° is carried into position against the opposite or upper face of the rib 14 as clearly indicated in Figure 2. The shoe during this movement revolving around the pin 10 into the new position, the shoe being then held stationary and having sliding contact with the trolley wire 15 as above described.

When desired the shoe may be dismounted from the harp and replaced so that the ribs 14 are located between any one of the other pairs of projections 13^x and 13°, thereby providing a new wearing surface forming sliding contact between the shoe and the trolley wire.

From this description it will be seen that I have devised a trolley shoe which will have a maximum number of wearing contact surfaces which may be used successively as each contact surface wears out, thereby increasing the life of the shoe to a maximum extent, and which will readily automatically adjust itself to forward and reversed movement whenever desired, and which in all positions will provide an efficient current conduction between the shoe and the harp.

What I claim as my invention is:

1. The combination with a trolley harp, of an annular shoe provided with a periph-

- 4 eral surrounding groove adapted to receive
a trolley wire, and means for holding the
shoe either in a stationary forward or re-
verse position and adapted to automatically
5 adjust itself to such forward and reverse
position upon the reversal of travel of the
trolley shoe when in sliding contact with
the trolley wire.
2. The combination with a trolley harp,
10 of an annular shoe provided with a periph-
eral surrounding groove adapted to receive
a trolley wire, and means adapted to hold

the shoe in a plurality of stationary pos-
itions for both forward and reverse move-
ment as the direction of the trolley shoe is
15 reversed.

3. The combination with a trolley harp,
of a circular trolley shoe turnably mounted
in the harp, stop means extending from the
shoe, and stationary stop means carried by
20 the harp to contact with the stop means on
the shoe either during forward or reverse
movement.

ROBERT JOHN LYLE.
